UNITED STATES PATENT OFFICE.

CHARLES F. SPERY, OF CHICAGO, ILLINOIS.

RADIATOR CORE.

Application filed March 9, 1922. Serial No. 542,330.

To all whom it may concern:

Be it known that I, CHARLES F. SPERY, a citizen of the United States, and resident of Chicago, in the county of Cook and State of Illinois, have invented new and useful Improvements in Radiator Cores, of which the following is a specification.

This invention relates to the construction of cores for radiators of the kind employed to form part of the water cooling system of internal combustion engines.

The object of the present invention is to provide a radiator core of simple and durable construction. A further object is the provision of a core which will thoroughly cool the water passing therethrough, such core having ribbon shaped water-channels the flat sides of which being able to yield to the expansion of the enclosed body of water, should the water accidentally freeze, thereby saving the core from bursting.

To this end I have provided a structure having water channels of a peculiar shape, and provided with spacing members shaped to direct air against the sides of the water channel, all as clearly set forth in the following detailed description, and illustrated in the appended drawing, of which:

Fig. 1 is a fragmentary front elevation, partly in section, of a radiator-core having its limits constructed and shaped in accordance with my invention. One of the units is shown partly in section in order to indicate the appearance of the water-channels,

Fig. 2 illustrates a pair of spacing members removed from the structure of Fig. 1 and shown slightly separated in order more clearly to indicate the various details of construction. One of the members is shown in cross-section substantially through its center,

Fig. 3 is a fragmentary side elevation of one of the spacing members just referred to, and

Fig. 4 is a corresponding side elevation of one of the side plates of a core unit.

The radiator of my invention is of a honey-comb shape, comprising a plurality of hexagonal cells combined into vertical units, each of which forms a separate self-supporting frame 1, 2, etc. When these frames are assembled it is to be noted that the adjacent frame sides combine to form water-channels 4, 5, etc. In order to provide the water space between the adjacent side plates necessary to provide thin ribbon-like water-channels, it is pointed out that

these side plates are made from a thin strip of metal, which is bent into the shape of a slender rectangular frame 7, closed at one end by a lock seam 8. Outwardly projecting from the sides of this frame are uniform transverse series of semi-hexagonal ridges 7^a, and it is important to note that the center portion of each series of ridges is somewhat depressed, as shown at 7^b in Fig. 4. The result is that the frames, when they are assembled side by side and soldered together, come into contact with each other only along the edges, where the solder flows in and forms a water-tight joint, and that the intermediate portion remains in spaced relation, forming the semi-hexagonal ribbon shaped passage for the water.

For the purpose of maintaining the units correctly assembled until the time that the solder hardens and ties them together permanently, I have provided inter-fitting semi-spherical extrusions, or buttons, 7^c, 7^d, uniformly spaced along the edges of the frame sides, and these buttons greatly facilitate the assembling operation. It is also to be observed that the top or bottom of one frame is narrow and that of the next following frame is wide, a condition which is incidental to the honey-comb shape, and necessary in order that the top and bottom surfaces of the whole core may be made flat and not crenelated yet all the frames of the core are exactly alike, but each alternate frame is turned upside down.

There is an empty space A within each frame, which space must be filled in some manner, or the thin metal of the frames will not retain its shape during the assembling and soldering operations, besides, without some proper filler, the honey-comb would be incomplete, insubstantial and not of a pleasing appearance. Into this space I insert a pair of thin metal spacing members 9, which members are exactly alike, and provided along their edges with extrusions, or buttons, 9^b, 9^c, for registration with the buttons 7^c, 7^d of the frame sides, whereby the said members are held in correct relation to the frames during the soldering operation. Each member is made with uniformly shaped and spaced semi-hexagonal projections along both front edges, and it is noticed that the apical surfaces 9^a of these projections abut the apical surfaces 7^a of the encompassing frame. Rising from the center portion of the front surface of these members is a cor-

responding series of transverse rhombic projections 9^a, arranged in staggered relation to said edge projections, in such a manner that the pointed ends 9^b of these rhombic projections commence to rise in the spaces 9^c between the hexagonal projections. When a pair of these spacing members are placed back to back, as in practice and as shown in Fig. 1, it is noticed that the semi-hexagonal 10 edge projections combine to form the series of cells required to fill the space within each frame, and it is further observed that the rhombic projections combine to form lozenge shaped bodies, each of which bodies takes a 15 central position within each large space between two adjacent water-channels.

Looking merely at the front (or back) of the core, the true honey-comb shape only is apparent, but by sighting through the 20 core, row after row of corrugated bands are observed, which bands are the walls of the water-channels, winding their way out and in from top to bottom in uniformly opposed succession. And in the center of each widening 25 is a lozenge-shaped body. But while the appearance of the structure is important, there is a distinct purpose in mounting these lozenge or torpedo-shaped bodies between the water-channels, and the purpose is 30 to split the air current rushing through the core, and to throw it against the sides of the water-channels. The exact cross-sectional shape of this lozenge-like deflector is not 35 important, so long as it operates to split the passing air, and the shape indicated in the drawing is merely illustrative of this function.

I claim—

1. In a radiator core, vertical series of 40 semi-hexagonal ribbon shaped water channels, the air-spaces between said channels alternately widening and narrowing from top to bottom, and lozenge shaped air deflecting bodies centrally positioned within 45 each widening.

2. In a radiator core, vertical series of 50 semi-hexagonal ribbon shaped water channels in opposed spaced relation, and spacing members between adjacent water-channels, said spacing members made with opposed 55 rhombic projections combining to form air deflectors centrally positioned within space enlargements between said water-channels.

3. In a radiator core, vertical series of 60 semi-hexagonal ribbon shaped water-channels so related that the air space between

each adjacent pair of water-channels alternately widens and contracts, and a spacer 60 between each pair of channels, said spacer having semi-hexagonal edge bands for engagement with edge bands of the water-channels and provided with lozenge-shaped deflectors centrally located within each space widening of the water-channels.

4. In a radiator core, vertical series of 65 semi-hexagonal ribbon shaped water-channels so related that the air space between each adjacent pair of water channels alternately widens and contracts, and a spacer 70 between each pair of channels, said spacer 75 comprising a pair of thin metal strips having semi-hexagonal edge projections and placed back to back so that the said projections combine to form a series of spaced hexagons the apices of which abut apices 80 of the water-channels, each spacer formed with a series of rhombic projections, said projections combining to form lozenge-shaped bodies positioned centrally within the water-channel widenings.

5. A radiator core comprising identical 85 vertically disposed sheet metal frames the sides of which are bent alternately in and out in opposite directions to form semi-hexagonal outlines, and assembled in alternate 90 reversed relation, a sheet metal spacer within each frame and having hexagonal edgebands abutting the inner faces of said frame sides, said spacer provided with projections 95 forming lozenge-shaped bodies centrally positioned within widenings between the frame sides, and means for alining the parts in assembling.

6. In a radiator core, vertical series of 100 semi-hexagonal ribbon shaped water-channels so related that the air space between each adjacent pair of water-channels alternately widens and contracts, and a spacer 105 between each pair of channels, said spacer having semi-hexagonal edge bands for engagement with edge bands of the water-channels and provided with lozenge-shaped deflectors centrally located within each space widening of the water-channels, the water channels and spacers provided with 110 interfitting alining means capable of maintaining the relations between the assembled parts until the core has passed through the soldering process.

In testimony whereof, I have hereunto affixed my signature.

CHARLES F. SPERY.
